CLAIM

The ornamental design for footwear, as shown and described.

DESCRIPTION

FIG. 1 is a lateral side view of footwear.

FIG. 2 is a medial side view of the footwear of FIG. 1.

FIG. 3 is a front view of the footwear of FIG. 1.

FIG. 4 is a rear view of the footwear of FIG. 1.

FIG. 5 is a top view of the footwear of FIG. 1; and,

FIG. 6 is a bottom view of the footwear of FIG. 1.

The dash-dot-dash line indicates an outer boundary of the claimed design. The portions of the footwear outside of that boundary are unclaimed.

1 Claim, 6 Drawing Sheets

FIG. 1

FIG. 2

FIG. 3

FIG. 4

FIG. 5

FIG. 6
